UNITED STATES PATENT OFFICE.

JOHN YOUNG AND JOHN HENRY GEIER, OF GALION, OHIO.

GRAVE-VAULT.

1,125,626.

Specification of Letters Patent. Patented Jan. 19, 1915.

Application filed March 2, 1914. Serial No. 822,046.

To all whom it may concern:

Be it known that we, JOHN YOUNG and JOHN HENRY GEIER, citizens of the United States of America, residing at Galion, in the county of Crawford and State of Ohio, have invented certain new and useful Improvements in Grave-Vaults, of which the following is a specification.

This invention has for an object to provide an improved door especially adapted for reliably locking and hermetically sealing the entrance to a grave vault.

Another object is to provide a vault door having adjustable means for either permanently or removably locking it in closed position.

These and other objects may be attained by means of the construction hereinafter more specifically described and illustrated in the accompanying drawing, in which,

Figure 1 represents a rear elevation and partial section of the grave vault and door in open position. Fig. 2 represents a central sectional view through the vault and door in closed and unlocked position. Fig. 3 represents a similar view showing the door locked. Fig. 4 represents an enlarged fragmentary sectional view showing a detail of the lock mechanism. Fig. 5 represents a front elevation of a part of the lock mechanism, and, Fig. 6 represents a rear elevation partly in section of a device for permanently locking the door.

Referring to the drawing in detail, where in similar reference numerals designate corresponding parts throughout the several views, 7 indicates the grave vault adjacent the open end of which is secured an angle bar 8 shaped in conformity therewith and providing an abutment for a door 9 supported upon hinges 10. The plane portion 11 of a screw 12 is rotatably mounted through the door 9 and is formed with a square outer end 13 for receiving the jaws

45 of a suitable operating wrench. A rubber or other washer 14 is disposed on the plane portion 11 of the screw between the inner face of the door 9 and the flange 15 and is adapted to be clamped between these parts by the action of a wedge 16 working through a collar 17 and an opening formed transversely in the outer end of the screw 12 and against the outer face of the door.

50 A series of substantially triangular locking members 18 is arranged on the inner

face of the door 9 and each member is formed adjacent its inner end with a slot 19 receiving a guide pin 20 suitably and rigidly secured to the door. Pairs of fingers 21 are formed on the outer edges of the locking members and are disposed under the heads 22 of T-bolts or the like 23 also secured to the door 9 and received between the fingers of each pair. The inner small ends of the triangular locking members 18 are disposed between the sleeve 24 and the inwardly directed flange 25 of a housing 26, and both the sleeve 24 and housing 26 are formed with threaded apertures snugly fitting the screw 12. The sleeve 24 is positioned within and rotatable with a member 29 and is formed with a pair of diametrically opposed ribs 27 extending parallel with the opening therethrough and received within suitable grooves formed in the wall of an opening 28 in the member 29 within which the sleeve 24 is slidable. The member 29 is formed with a plurality of radially extending spokes or arms 30 carrying laterally projecting pins 31 at their outer ends received and slidable within slots 32 formed in the adjacent portions of the members 18.

The housing 26 is prevented from rotating with the screw 12 by pins 33 extending through the flange 25 and projecting into slots 34 formed in the adjacent portions of the locking members 18. A spring actuated pawl 35 is pivoted at 36 to the inner face of the housing 26 and is adapted to coöperate with the teeth 37 formed longitudinally of the threaded end of the screw 12 for preventing rotation thereof in one direction, as will be hereinafter set forth. The free end of the pawl 35 is connected with a sleeve 38 slidably mounted within an angle opening 39 in the housing 26 for raising the pawl 35 and securing it out of the engagements with the teeth 37.

In operation, the door is closed as shown in Fig. 2 and the screw 12 rotated by a suitable wrench applied to the square end 13 thereof. Owing to the snug frictional engagement of the screw 12 with the sleeve 24, the latter is rotated with said screw, carrying therewith the member 29. The pins 31 of the member 29 working within the slots 32 throw the locking members 18 outwardly carrying the fingers 21 behind the inwardly directed flange at the angle of the bar 8,

thus locking the door 9 in closed position. When the pins 31 engage the opposite ends of the slots 32 the rotary movement of the sleeve 24 and member 29 is stopped and subsequent rotation of the screw 12 advances the housing 26 and sleeve 24 inwardly of the vault on the threads of the screw 12 and moves therewith the interposed inner ends of the locking members 18. The heads of the bolts 25 act as fulcrums for the members 18 and cause the fingers 21 to move against the inner face of the flange of the bar 8 as the inner extremities of the locking members 18 are moved inwardly and thus draw the door 9 firmly against the gasket 40 disposed between said bar and door. The spring actuated pawl 35 normally engages the teeth 37 of the screw 12 and prevents the latter from being rotated in a reverse direction to retract locking members 18, but may be secured in inoperative position by sliding the sleeve 38 outwardly in the angular opening 39, thus permitting the door to be locked and unlocked as many times as desired.

Copies of this patent may be obtained for five cents each, by addressing the "Commissioner of Patents, Washington, D. C."

What we claim is:—

A vault door provided with a centrally located rotatable screw having an integral flange intermediate its ends, a series of locking members having sliding and pivotal movements on the inside of said door, a sleeve snugly fitted on said rotatable screw between said locking members and said flange, means non-rotatably and slidably mounted on said sleeve having connection with said locking members for extending the latter into locked position when said screw is rotated, a housing fitted on the inner end of said screw, means for non-rotatably securing said housing to said locking members, and means carried by said housing for locking said screw against rotation in one direction.

In testimony whereof we affix our signatures in presence of two witnesses.

JOHN YOUNG.
JOHN HENRY GEIER.
